CLAIM

The ornamental design for a loudspeaker, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front, top, side perspective view of a first embodiment of a loudspeaker showing the new design; FIG. 2 is a front, top, opposite-side perspective view thereof; FIG. 3 is a front, top, side perspective view of a second embodiment of a loudspeaker showing the new design; and, FIG. 4 is a front, top, opposite-side perspective view thereof. The dash-dot broken lines in the figures represent the boundaries of the claimed design and form no part of the claimed design. The evenly spaced broken lines in the figures illustrate portions of the loudspeaker and form no part of the claimed design. The lightened gray areas outside of the dash-dot boundary lines and inside the evenly spaced broken lines, illustrate environmental subject matter that forms no part of the claimed design. None of the broken lines forms any part of the claimed design.
